BAILER DUMP BOTTOM

Warren M. Zingg, Tulsa, Okla., assignor to The Dow Chemical Company, Midland, Mich., a corporation of Delaware

Filed Dec. 27, 1967, Ser. No. 693,812

Int. Cl. E21b 43/04, 23/06

U.S. Cl. 294—69

4 Claims

ABSTRACT OF THE DISCLOSURE

The invention relates to dump bailers for use in earth wells. The bailers have a full opening trap at the bottom which is opened by pressing a downwardly extending trigger element against an obstruction across the bore hole, thus moving the trigger element and disengaging the trap from a sear on the trigger element. Thus, bagged goods in the bailed may be discharged by withdrawing the bailed up the bore hole.

This invention relates to dump bailers and particularly to dump bailers of the full open discharge type.

Most dump bailers are of the dart type and are capable of handling fluid or a slurry as long as the nature of the fluid is such that it will flow through and around the dart.

Glass bottom bailers have been used to run gravel, rock, etc. to the bottom of a well bore by setting down the bailed hard enough to break the glass. Neither of these methods are satisfactory where bags of blasting agent comprising an ammonium nitrate based explosive containing water, other liquid extenders, particulate metal, and thickening agents (other sensitizing agents also can be included), for example, are to be deposited at predetermined positions in a well bore.

Accordingly, a principal object of this invention is to provide an improved full open discharge type dump bailed.

A further object of this invention is to provide an improved dump bailed which is adapted to carry and dump bagged material.

In accordance with this invention, there is provided an elongated tubular bailed having cable attachment means at one open end part and a full open discharge means including a pivotally held flapper closure element which is retained in position by a sear element disposed on a trigger arm which is pivotally attached to the side wall of the bailed.

When the trigger arm is depressed upwardly, the resulting movement of the sear element disengages the edge of the flapper which is disposed opposite to the flapper pivot, dropping the flapper and opening the bottom of the bailed.

The invention, as well as additional objects and advantages thereof, will best be understood when the following detailed description is read in connection with the accompanying drawing, in which:

FIG. 1 is a side elevational view, in section, of a bailed in accordance with this invention;

FIG. 2 is a fragmentary view, partly broken away and in section, of the lower end of the bailed shown in FIG. 1, and

FIG. 3 is a fragmentary sectional view taken along the line 3—3 of FIG. 2.

Referring to the drawing, there is shown a dump bailed, indicated generally by the numeral 10, comprising an elongated tubular body part 12. A cable attachment loop 14 is secured to the upper end of the body section 12. A tubular bottom section 16, fixedly coupled to the lower part of the body section 12, contains a dump assembly

2

comprising a flapper type closure member 32 which has a neck 38 which is pivotally coupled by means of the rod 30 which extends through the bore 40 in the neck 38 and through bores 42, 44 in the wall of the bottom section 16. The side wall of the bottom section 16 has a longitudinally extending slot 46 into which the neck 38 fits.

The lower end of the bottom section 16 is cut away from just below the bores 42, 44 to near the center of the bottom 48 of the section.

10 A trigger arm, 20, has an elongated part 21 to which is attached a plate 18 which presents a wider surface than that of the arm to any obstruction it meets as the bailed is lowered in a bore hole.

15 The trigger arm has a part 34 which, when it engages and holds the flapper type closure member 32, is disposed in alignment with the longitudinal axis of the bailed. The part 34 contains a notch 22 on which rests the edge of the member 32 which is opposite the neck 38. The depth and walls of the notch 22 are such that material contained in the bailed may not force the flapper closure member 32 over-center.

20 The trigger arm 20 is pivoted through the part 34 by means of a pin 24 extending through the walls of the section 16 and across the longitudinally extending slot 26 in the bottom part of the section 16, in the same manner as shown in FIG. 3, for example.

25 The elongated part 21 of the trigger is disposed at an angle of about 135 degrees as measured between the notch 22 and the plate 18.

30 In operation, the bailed 10, loaded with packaged materials which rests against the closure member 32 which is held in position across the bailed by the notch 22 in the trigger arm 20.

35 As the plate 18 bears against the bottom of the bore hole (not shown) or against material present in the bore hole, the trigger arm 20 is moved upwardly, moving the notch 22 on the part 34 away from the edge of the flapper closure member 32.

40 As the notch 22 moves, the edge of the flapper member 32 is released, dropping the flapper closure member 32 so that it is more or less aligned with the side wall of the bailed 10. As the flapper closure member 32 is released, the trigger arm 20 drops downwardly, leaving a more or less full open discharge path for the release from the bailed of the packaged goods contained therein.

45 Thus, it may be seen that this invention provides a simple, fool proof full opening dump bailed bottom.

What is claimed is:

1. A dump bailed comprising an elongated tubular body having side walls, top part and bottom part, cable attachment means secured to said top part, and a releasable closure mechanism at said bottom part, said closure mechanism including a pair of diametrically opposed slots extending upwardly from the lower end of said bottom part, one of said slots extending above the other slot, a flapper type closure element having a pivotable coupling at one end thereof, said coupling being secured to said side wall adjacent to and aligned with said slot which extends above the other slot and having an opposed edge, a trigger assembly comprising an elongated arm section and a shorter arm section, said arm sections being rigidly coupled together at an included angle which is between 110° and 150°, said shorter arm being pivotally coupled with respect to said body adjacent to and in alignment with said other slot, said shorter arm having a notch facing and engaging said opposed edge when said elongated arm extends below said body at an angle of between 110° and 150° with respect to the longitudinal axis of said body.

2. A dump bailed in accordance with claim 1, wherein said included angle is approximately 135°.

3. A dump bailer in accordance with claim 1, wherein said elongated arm extends below said body at an angle of approximately 135 degrees with respect to the longitudinal axis of said body when said notch is in its stable flapper closure element retaining position.

4. A dump bailer in accordance with claim 1, wherein the length of said shorter arm is substantially greater than the thickness of said flapper element.
